(57) **CLAIM**

The ornamental design for a game controller, as shown and described.

DESCRIPTION

FIG. 1 is a rear and bottom perspective view of a first embodiment of a game controller, showing our new design; FIG. 2 is a rear and top perspective view thereof; FIG. 3 is a bottom view thereof; FIG. 4 is a top view thereof; FIG. 5 is a left side view thereof; FIG. 6 is a right side view thereof; FIG. 7 is a front elevational view thereof; FIG. 8 is a rear elevational view thereof; FIG. 9 is a rear and bottom perspective view of a second embodiment of a game controller, showing our new design; FIG. 10 is a rear and top perspective view thereof; FIG. 11 is a bottom view thereof; FIG. 12 is a top view thereof; FIG. 13 is a left side view thereof; FIG. 14 is a right side view thereof; FIG. 15 is a front elevational view thereof; and, FIG. 16 is a rear elevational view thereof.

The broken line showing of a game controller is included for the purpose of illustrating portions of the article and forms no part of the claimed design.

1 Claim, 16 Drawing Sheets
